PAGE 2

Fig. 2

To all whom it may concern:

Be it known that I, Marcus Tomarin, a citizen of the United States, residing at Cincinnati, in the county of Hamilton and State of Ohio, have invented a new, original, and ornamental Design for a Pipe Expander or the like, of which the following is a specification, reference being had to the accompanying drawings, forming part thereof.

Fig. 1 is a perspective view of the left front of a pipe expander or the like, showing my new design.

Fig. 2 is a perspective view of the right rear of the device of Fig. 1.

Fig. 3 is a bottom view of Fig. 2.

I claim:

The ornamental design for a pipe expander or the like, as shown.
